Inventor

H. N. May
by James J. Sherry, Jr., Attorney.

UNITED STATES PATENT OFFICE.

HAROLD N. MAY, OF NEW ORLEANS, LOUISIANA.

ADJUSTABLE CURTAIN CARRIER.

Application filed July 24, 1922. Serial No. 577,113.

To all whom it may concern:

Be it known that I, HAROLD N. MAY, a citizen of the United States, residing at New Orleans, in the parish of Orleans and State 5 of Louisiana, have invented new and useful Improvements in Adjustable Curtain Carriers, of which the following is a specification.

My present invention pertains to adjustable curtain rods for motor vehicles or the like and it contemplates the provision of a device through the medium of which the annoyance attending the positioning of a storm curtain at short notice is eliminated.

15 The invention further contemplates the provision of an adjustable curtain rod that is easily operated and installed and when the storm curtain is not in use the same may be pushed into a position out of the way of 20 persons occupying the vehicle.

The invention further contemplates the provision of a device for the purpose set forth whereby the storm curtain may be quickly and easily removed from the rod if 25 so desired, and one that adds rather than detracts from the finished appearance of a vehicle.

Other objects and advantageous features 30 of the invention will be fully understood from the following description and claims when the same are read in connection with the drawings accompanying and forming part of this specification, in which—

Figure 1 is a side elevation showing my 35 novel curtain rod with a curtain secured thereto and also illustrating the manner in which the rod is secured to the rafters of a vehicle top.

Figure 2 is a sectional view of Figure 1. 40 Figure 3 is a detail view of the spacing post of the device.

Similar numerals of reference designate corresponding parts in all the views of the drawings.

45 My novel rod comprises the inner casing or member 1 that is turned at its upper end 2 and its lower end 3 and between its rolled ends the casing 1 is provided with the track portion 7. Adapted to surround and slide 50 longitudinally with respect to the inner casing 1 is an outer casing 4 having the bent upper end 5 that corresponds to the bent upper end 2 of the casing 1 and the lower bent portion 6 that corresponds to the lower 55 bent portion 3 of the casing 1. The outer

casing 4 is further provided with the rolled portion 8 that travels in the track portion 7 and manifestly the length of the rod as a whole may be increased or decreased by moving one casing along the other.

60 Adapted to rest between the tracks 7 of the casing 1 is my novel curtain holding device which comprises the frame 9 having the rollers or wheels 10 provided with the kerf through the medium of which said wheels straddle and travel over the track 7 of the casing 1. In order to prevent the wheels from casually falling from the track I provide the post 11 that is secured to the lower frame 9 and passes through the upper frame 70 9 and the said post is provided with a head or stud 11^a that bears against the upper rail 7 or 8 according to the position of the curtain holder with respect to the rails. It will be manifest by reference to the drawings that a compression spring 12 surrounds the post 11 and bears at its upper end against the lower face of the upper frame 9 and at its lower end against the upper face of the lower frame 9 and manifestly this 80 construction will tend to force the frames 9 away from each other and will also cause the rollers 11 to hug their adjacent rails. The wheels 10 seat in bifurcations formed in the ends of the frames 9.

85 Secured in permanent manner, if desired, to the lower frame 9, is a hook 13 that is open to receive a hook 14 and the said hook 14 is permanently secured to a curtain rail or frame 15 that is provided with apertures through which pass rivets or other fastening means 16 whereby a curtain is secured to the rail 15. At this point, I would distinctly have it understood that I do not care to confine myself to any particular style of hook 90 13, hook 14 and rail 15 or fastening means 16 as in the future practice of the invention any style of hook and means of fastening same to its complementary member may be employed as fairly fall within the scope of 100 the appended claims.

105 The entire device may be permanently or removably secured to a rafter 21 of a vehicle top by means of the hanger 18 which is adapted to surround the rafter and be securely and removably adjusted thereto by means of the bolt 20 that passes through apertures in the ears 19 of the hanger 18. By reference to Figures 1 and 2 it will be seen that the casing 4 as well as the casing 110

1 are each provided with apertures to receive studs or fastening devices 22. Manifestly the casings may be securely held in a permanent or removable manner on the hanger 18.

In the practical use of the invention, the hanger with the curtain carrier casings secured thereto is positioned so as to grip the rafter 21 and the nut of the bolt 20 is turned 10 so as to prevent creeping of the hanger. When this has been done and occasion demands it is simply necessary to hook the curtain 17 to the element 13 of the carriage and the curtain may be moved parallel with 15 respect to the rafter with little effort.

It will be manifest that the curtain carriage as well as the rafter gripping element and inner and outer casings are out of the way at all times and that the curtain 20 may be quickly adjusted on the carrier and should the rollers 10 of the frames 9 leave the rail or strike an obstruction it is merely necessary to force the frames 9 toward each other by exerting pressure on the spring 12. Under normal conditions the spring 12 25 will preclude liability of the rollers leaving the rail and will also materially decrease the noise incident to the operations of a motor vehicle.

30 The invention is simple in construction and easily operated and will add rather than detract from the finished appearance of a motor vehicle.

Having described my invention, what I

claim and desire to secure by Letters Patent 35 is:—

1. In a device for the purpose set forth, the combination of telescoping sections having rails formed therein, a carriage adapted 40 to rest between the rails and comprising upper and lower bars, rollers secured to the bars, a post extending from one to the other of the bars, a compression spring surrounding the post and bearing at its ends against the bars to force the rollers against the 45 rails, and a clip permanently secured to the lower bar and adapted to receive a storm curtain.

2. In a device for the purpose set forth, the combination of adjustable sections, rails 50 formed on the sections and a carriage resting on the rails; said carriage comprising upper and lower bars, rollers secured to the bars, a post permanently secured to the lower bar and passing through an opening in the upper bar, a spring surrounding the post and bearing against the bars whereby the rollers are prevented from casually falling 55 from the rails and means secured to one of the bars for the removable attachment of a storm curtain.

In testimony whereof I have hereunto set my hand in presence of two subscribing witnesses.

HAROLD N. MAY.
